UNITED STATES PATENT OFFICE.

JOSEPH PASCOE, OF MINNEAPOLIS, MINNESOTA.

DOOR CONSTRUCTION FOR SILOS.

Specification of Letters Patent.

Patented Jan. 26, 1915.

1,126,653.

Application filed May 7, 1914. Serial No. 837,025.

To all whom it may concern:

Be it known that I, JOSEPH PASCOE, of Minneapolis, in the county of Hennepin and State of Minnesota, have invented certain new and useful Improvements in Door Constructions for Silos, &c.; and I do hereby declare the following to be a full, clear, and exact description of the invention, such as will enable others skilled in the art to which it appertains to make and use the same.

10 This invention relates to improvements in door constructions for silos and kindred cylindrical structures,—one object of the invention being to provide a double door structure in which two doors arranged in superposed relation to each other shall be so constructed and mounted that the lower door cannot be opened until the upper door shall have first been opened, and so that when 15 cross bars on said doors are used as the rungs of a ladder, the weight will be transmitted directly to the lower breast plate or sill of the frame and the hinges be thus relieved from strain or sagging which would be otherwise incident to downward pressure upon 20 the doors.

A further object is to provide simple and efficient means for hinging superposed doors of the character specified so that the doors 25 may be opened or closed independently without binding conflict with each other, and at the same time utilize a single shaft to form the pintle partitions of the hinges of both doors.

30 With these and other objects in view, the invention consists in certain novel features of construction and combinations of parts as hereinafter set forth and pointed out in the claims.

35 In the accompanying drawings, Figure 1 is a front elevation showing a door structure embodying my improvements; Fig. 2 is a vertical sectional view; Fig. 3 is a horizontal sectional view, and Fig. 4 is a fragmentary view showing the manner of connecting the hinge bails 11 and 12 with the shaft 10.

40 1, 1, represent the uprights or stiles of the door frame of a silo or similar structure,—50 the sill and crown rail of said frame being formed by bars or breast plates 2, 3 bolted to the stiles and having their inner straight portions disposed between the inner edges of the stiles and extending from one to the other to form abutments for doors 6, 7 as 55 shown in Fig. 2. It will be understood that

a silo will be provided with a vertical series of such door frames as above described, and each cross-bar or breast plate, except those at the top and bottom of the series, may be 60 made to serve both as a sill for one frame and a crown rail for the next lower frame.

Two hinged doors 6, 7 are provided for each door opening and these doors are disposed in superposed relation to each other,—65 the lower edge of the upper door 6 being recessed to form a depending flange 8 to engage an upwardly projecting flange 9 formed by recessing the upper edge of the lower door 7, so as to prevent the lower door 70 from being opened until the upper door shall have been first opened, or both doors may be opened simultaneously.

A single shaft 10 is revolvably mounted at its ends between the sill and crown rail in 75 proximity to one of the stiles, and the arms of bails 11—12 pivotally attached to the respective doors, are connected. The arms of the bail 11 for the upper door 6 are rigidly secured to the shaft 10 so that when said upper door is opened or closed the shaft will 80 be rotated. The arms of the bail 12 for the lower door 7 are provided at their free ends with eyes 13 which loosely embrace the shaft so as to turn freely therein. Thus the upper 85 door may be swung independently of the lower door, and the latter may be swung independently of the upper door when the latter is open. It will thus be seen that my 90 improvements provide hinge connections 90 which permit the separate swinging of the two doors, and that the single shaft 10 serves as the pintle portion of both hinge structures.

Each of the two superposed doors is provided on its outer face near its respective edges with vertical cleats 14, 14,—the cleats of the upper door alining with and adapted to rest upon the cleats 14 of the lower door, and the cleats of the lower door being adapted to rest upon the sill. The cleats 14—14 of each door are connected by cross-bars 15 secured thereto by bolts 16 and on these same bolts, latch levers 17 are mounted and adapted to coöperate with beveled plates 18 on the 100 stiles to secure the doors in closed position.

105 The cross-bars 15 constitute the rungs of a ladder, and by the arrangement of cleats above described, the weight applied to these cross-bars or rungs will come upon the alining cleats and be sustained by the solid abutment of the cleats of the lower door upon the 110

sill of the door frame,—thus relieving the hinge mountings from all strain which might otherwise be incident to the application of weight vertically upon the doors, and therefore the doors are not liable to sag but will always swing pr perly and close truly against their seats.

Slight changes might be made in the details of construction of my invention without departing from the spirit thereof or limiting its scope and hence I do not wish to restrict myself to the precise details herein set forth.

Having fully described my invention what I claim as new and desire to secure by Letters Patent, is:

1. A silo having an opening spanned by sills of standard spacing, a vertical pintle rod mounted between each pair of adjacent sills, a lower door mounted on hinges playing on such pintle rod and its lower end engageable with the lower sill to prevent sagging, and an independent upper door mounted on hinge arms rigid with said

pintle rod to prevent sagging and positioned to accurately engage the upper end of and be supported by the lower door when the latter is in place upon the sill. 25

2. A silo having an opening spanned by sills of standard spacing, a vertical pintle rod mounted between each pair of adjacent sills, a lower door mounted on hinges playing on said pintle rod, vertical cleats on said lower door to rest on the lower sill, an upper door mounted on hinge arms rigid with said pintle rod, vertical cleats on said upper door to rest upon the cleats on the lower door when both doors are closed, and cross bars secured to and spanning the pair of cleats on each of said doors. 30 35 40

In testimony whereof, I have signed this specification in the presence of two subscribing witnesses.

JOSEPH PASCOE.
